UNITED STATES PATENT OFFICE

171,928

COMBINATION GARMENT AND TIE RACK

Achille G. Bureau, Forest Hills, N. Y.

Application January 21, 1954, Serial No. 28,624

Term of patent 3½ years

(Cl. D33—8)

To all whom it may concern:

Be it known that I, Achille G. Bureau, a citizen of the United States of America, residing at 374 Burns Street, Forest Hills 75, county of Queens, State of New York, have invented a new, original, and ornamental Design for a Combination Garment and Tie Rack, of which the following is a specification, reference being made to the accompanying drawing, forming part thereof:

Fig. 1 is a front elevational view of a combination garment and tie rack showing my new design;

Fig. 2 is a top plan view;

Fig. 3 is a side elevational view.

I claim:

The ornamental design for a combination garment and tie rack, substantially as shown.
